CLAIM

The ornamental design for a bridge shelf, as shown and described.

DESCRIPTION

FIG. 1 is a front top perspective view of a bridge shelf showing one embodiment of our new design.

FIG. 2 is a rear bottom perspective view of the bridge shelf of FIG. 1.

FIG. 3 is a top view of the bridge shelf of FIG. 1.

FIG. 4 is a bottom view of the bridge shelf of FIG. 1.

FIG. 5 is a left view of the bridge shelf of FIG. 1.

FIG. 6 is a right view of the bridge shelf of FIG. 1.

FIG. 7 is a front view of the bridge shelf of FIG. 1.

FIG. 8 is a rear view of the bridge shelf of FIG. 1; and, FIG. 9 is a perspective view of a shelving system which incorporates the bridge shelf of FIG. 1.

The broken lines showing in FIG. 9 are for the purposes of illustrating the environment of the article only and form no part of the claimed design.
